SAFETY RAZOR BLADE SHARPENER

Donald Clark, Valencia, Pa.

Application April 17, 1942, Serial No. 439,406

2 Claims. (Cl. 51—218)

This invention relates to safety razor blade sharpeners and more particularly to a holder for safety razor and other type blades, and has for the primary object the provision of a holder of this character which will efficiently support one or more blades against movement with the cutting edges thereof located for sharpening by a manually operated hone and also will act to guide the manually moved hone to assure correct sharpening of the cutting edges.

Another object of this invention is the provision of a holder of the above stated character which may be economically manufactured to permit selling thereof at a low cost, so that anyone desiring to sharpen used blades may do so and with the assurance that the blades will be made as sharp as they were when originally bought.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which

Figure 1 is a side elevation illustrating a holder for blades constructed in accordance with my invention.

Figure 2 is a top plan view showing the holder with blades mounted thereon and clamped thereto.

Figure 3 is a bottom plan view illustrating the holder.

Figure 4 is a vertical sectional view taken on the line 4—4 of Figure 2.

Figure 5 is an end elevation illustrating the holder.

Figure 6 is a transverse sectional view showing the holder with blades thereon and a manually operated hone guided by said holder.

Figure 7 is a perspective view illustrating the holder with the clamping means removed.

Referring in detail to the drawings, the numeral 5 indicates an elongated base constructed of wood or any other material suitable for the purpose. The base 5 is provided with a cutaway portion to form spaced rests 6 and a clearance for the accommodation of securing nuts 7 preferably of the wing type. The top face of the body 5 is provided with a recess or groove 8 extending longitudinally of the base and for the full length thereof for the purpose of receiving a flat supporting plate 9 constructed of any

material suitable for the purpose and preferably metal.

The top face of the supporting plate 9 is substantially flush with the top face of the base 5 and has riveted or otherwise secured thereto a pair of studs or headed bolts 10, embedded in the base 5 and also is provided with a series of openings 11 grouped in pairs as shown in Figure 4.

The base 5 has a pair of openings 12 and a pair of sockets 13. The openings and sockets of the base align with the openings formed in the supporting plate 9. The base 5 is bored to receive the bolts 10 and in such a manner that the heads of the bolts are countersunk. The recesses for the countersinking of the heads of the bolts are preferably filled with a suitable material after the bolts have been placed in the base and riveted to the supporting plate.

A wear plate 14 engages with the under face of the base within the cutaway portion or between the rests and is provided with openings. The wear plate 14 is engaged by the wing nuts 7 to prevent said nuts from cutting into the base.

The top face of the base is provided with beveled faces 15 arranged at opposite sides of the groove 8 and the opposite side edges of the supporting plate. The beveled faces 15 terminate short of the ends of the base, as clearly shown in Figure 7.

The base 5 may be made of any length suitable for the purpose, so that one or more blades may be accommodated thereon or to rest flatly upon the top face of the supporting plate 9.

A clamping plate 16 is employed for securing the blades flatly upon the supporting plate 9 and has secured thereto short studs 17 which pass through openings in the supporting plate and are received within the recesses 13 of the base. The clamping plate 16 also has secured thereto long studs 18 provided with screw threads and extend through openings of the supporting plate, base 5 and wear plate 14 and have the wing nuts 7 threaded thereon.

The wing nuts when turned tightly against the wear plate 14 on the studs 18, will draw the clamping plate tightly on the blade and thereby firmly secure said blade on the supporting plate against accidental movement and with the cutting edges thereof disposed over the beveled faces 15 of the base 5. The thickness of the supporting plate is such as to support or guide a manually operated hone 19 over cutting edges of the blade for the purpose of sharpening said edges, the beveled faces 15 giving clearance for the

hone during its movement and its guidance by the clamping plate.

Thus it will be seen that a very efficient holder has been provided which will accommodate one or more blades and firmly secure said blades against movement relative thereto. Also, it will be seen that the clamping plate besides firmly securing the blades in position, also acts as a guide for the movement of the hone in relation to the cutting edges of the blade so as to efficiently sharpen the edges ready for stropping.

Therefore, it will be seen that a very efficient and practical holder has been provided for the blades, one that may be manufactured at a low cost to permit the selling thereof at a low price placing such a device within financial reach of everyone who desires to sharpen their blades after becoming dull. It is to be understood that after the blades have been sharpened on the holder, they can be easily removed and stropped to provide keen cutting edges thereto.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a holder for blades, an elongated base provided with a groove in the top face thereof, a supporting plate located in said groove and having the top face thereof substantially flush with the top face of the base, means securing the plate to

the base, a clamping plate for securing a blade on the plate, threaded studs secured to the clamping plate and extending through the blade, supporting plate and base, wing nuts threaded on said studs, said clamping plate being of a thickness to support a manually operated hone at a selected angle with respect to the base and cutting edges of the blade, and studs formed on said clamping plate and extending through the blade and supporting plate into said base, said base having a cutaway portion providing end supporting members and a recess therebetween to accommodate the wing nuts.

2. In a holder for blades, an elongated base provided with a groove in the top face thereof, a supporting plate located in said groove and having the top face thereof substantially flush with the top face of the base, means securing the plate to the base, a clamping plate for securing blades on the plate, threaded studs secured to the clamping plate and extending through the blades, supporting plate and base, wing nuts threaded on said studs, said clamping plate being of a thickness to support a manually operated hone at a selected angle with respect to the base and cutting edges of the blades, studs formed on said clamping plate and extending through the blades and supporting plate into said base, said base having a cutaway portion providing spaced rests and clearance for the nuts, and a wear plate secured to the base within the cutaway portion and adapted to have the first-named studs extending therethrough and to be engaged by the nuts.

DONALD CLARK.
